DESIGN FOR A TACK HAMMER

Charles W. Kegg, Huntington, Ind.

Application November 9, 1943, Serial No. 111,634

Term of patent 7 years

(Cl. D93—4)

To all whom it may concern:

Be it known that I, Charles W. Kegg, a citizen of the United States, residing at Huntington, in the county of Huntington and State of Indiana, have invented a new, original and ornamental Design for Tack Hammers, of which the following is a specification, reference being had to the accompanying drawing, forming part thereof.

Figure 1 is a side elevational view of a tack hammer, showing my new design and Figure 2 is a plan view.

I claim:

The ornamental design for a tack hammer, as shown.

CHARLES W. KEGG.
